(57) **CLAIM**

The ornamental design for a mobile phone, as shown and described.

DESCRIPTION

FIG. 1 is a rear perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front perspective view thereof.

The broken lines shown within the claimed design that are immediately adjacent to the shaded areas and define unshaded regions represent boundaries of the claim while all other broken lines are directed to environment; the broken lines form no part of the claimed design.

The dot-dash broken line surrounding the claimed design represents the outer boundary of the claimed design and forms no part thereof.
